UNITED STATES PATENT OFFICE.

ISABELL ALLEN, OF KANSAS CITY, MISSOURI, AND GEORGE HANLON, OF SHAWNEETOWN, ILLINOIS.

ELECTRIC CURLING-IRON.

No. 857,569.

Specification of Letters Patent.

Patented June 25, 1907.

Application filed October 16, 1906. Serial No. 339,256.

To all whom it may concern:

Be it known that we, ISABELL ALLEN and GEORGE HANLON, both citizens of the United States, and residents of Kansas City, Missouri, and Shawneetown, Illinois, respectively, have invented certain new and useful Improvements in Electric Curling-Irons, of which the following is a specification containing a full, clear, and exact description, reference being had to the accompanying drawings, forming a part hereof.

Our invention relates to an electric curling iron, and consists in a hair curling iron whereby the voltage of an ordinary incandescent lamp circuit is utilized in heating the main tube or body of the curling iron.

The principal object of our invention is to provide an electric curling iron wherein different degrees of heat may be readily obtained, which arrangement is essential in the practical and successful operation of an electric curling iron.

To the above purposes, our invention consists in certain novel features of construction and arrangement of parts, which will be hereinafter more fully set forth, pointed out in the claims, and illustrated in the accompanying drawings, in which:

Figure 1 is a side elevation of an electric curling iron of our improved construction; Fig. 2 is a plan view of the curling iron with one leg of the tongs swung around at right angles to the main leg or tube; Fig. 3 is an enlarged horizontal section taken through the center of the curling iron; Fig. 4 is an enlarged transverse section taken on the line 4-4 of Fig. 1; Fig. 5 is a horizontal section taken through the center of a hair crimper constructed in accordance with our invention.

Referring by numerals to the accompanying drawings:—1 designates the cylindrical handle of the iron, the forward end 2 of which is reduced in diameter relative to the main body portion of said handle, and removably seated in said reduced forward end is a tube 3, the forward end of which is open, and which forms the main leg of the curling iron.

Located on the interior of the forward end 2 of the handle, immediately to the rear of the tube 3, is a disk 4 of insulation, in which is removably seated the rear end of a tube 5, of glass, porcelain, or analogous insulating material, the exterior of which is threaded,

as designated by 6, and on which is wound the body portions of three non-insulated wires 7, 8, and 9, constructed of material of varying conductivity. These various wires are thus provided in order to vary the resistance of the electric current passing through the wires, and in turn vary the degree of heat obtained on the interior of the tube 3.

The three wires, after being wound the entire length of the tube 5, are connected at the outer end thereof to an insulated wire 10, which leads through said tube 5, and through the handle 1. Located in the rear end of said handle 1 is a disk 11 of insulation, on the outer face of which is provided a contact plate 12, to which the end of the wire 10 is connected.

Located in the forward end of the handle 1 is a block 13 of insulation, in the outer face of which is arranged three plates 14, 15, and 16, to which are connected respectively the ends of the wires 7, 8, and 9.

Formed through the forward portion of the handle 1 is a slot 17, through which operates a pin 18, the inner end of which is adapted to contact with the plates 14, 15 and 16, and the outer end of said pin being provided with a button 19.

Connected to the pin 18 is the forward end of a conductor 20, which is extended through the handle 1, through the disk 11, and is attached to a contact plate 21.

Removably positioned in the rear end of the handle 1 is a plug 22, on the inner end of which is fixed contact plates 23 and 24, which are adapted to contact respectively with the contact plates 21 and 12, and to which plates 23 and 24 are connected the ends of conductors 25 which extend outwardly through the plug 22, and which are connected at their opposite ends to an ordinary incandescent lamp circuit, or other suitable source of electrical supply.

Pivotedly mounted on the forward end 2 of the handle 1 by means of a screw or rivet 26 is a plate 27, the forward end of which is provided with a pair of ears 28, between which is fulcrumed the rear end of the swinging jaw or leg 29 of the curling iron, which jaw or leg is curved in cross section and adapted to fit over the tube 3. The rear end of this jaw or leg extends upwardly and rearwardly from the pivot point, and a spring 30 is interposed

between said upwardly and rearwardly extended end and the plate 27, the tendency of which spring causes the body portion of the leg or jaw 29 to yieldingly engage on the 5 face of the tube 23.

The operation of our improved curling iron is as follows: When the plug 22 is inserted in the rear end of the handle so that the contact plates 23 and 24 engage against the contact 10 plates 12 and 21, the current from one of the wires 25 will pass into and through the conductor 20, from thence through the pin 18 to one of the contact plates 14, 15, or 16, with which said pin is engaged, and from thence 15 through the corresponding one of the wires 7, 8, and 9, to the coiled portion thereof on the tube 5, and this portion of said wire acting as a resistance will become heated, and consequently heat the tube 3. The return current 20 passes through the conductor 10 and corresponding pair of contact plates at the rear end of the handle, and out through the corresponding one of the wires 25. The degree of heat obtained is varied by shifting the pin 18 25 backwardly or forwardly by means of the button 19, thus throwing into service the desired one of the wires 7, 8, and 9, which, as stated, vary in size or resistance to the electrical current, and thereby differentiate the 30 degree of heat. The swinging leg 29 of the curling iron is depressed at the rear end thereof, and the hair to be curled is engaged between said swinging leg and the tube 3, and after said hair is wrapped or curled upon 35 said tube and leg in the usual manner and held for a short time, the heat of the tube 3 very effectually curls said hair.

If desired, the plate 27 can be swung around at right angles to the handle 1, as 40 shown in Fig. 2, and the hair curled upon the tube 3, after which the plate 27 is moved into its normal position, and the leg 29 allowed to reengage upon the tube 3 to hold the hair thereon.

45 In Fig. 5 I have shown an arrangement for

crimping hair, which comprises three fixed fingers, provided with a shank adapted to be detachably seated in the forward end 2 of the handle 1, and there being a pair of hinged fingers adapted to engage between said fixed 50 fingers to crimp the hair. In this form of the device, the fixed fingers are heated by internal electric wires which receive current through the wires located in the handle 1.

A curling iron of our improved construction is simple, inexpensive, easily manipulated, can be very quickly heated by the current ordinarily utilized in incandescent lamp circuits, and the degree of heat in the iron can be varied according to the number of resistance wires or coils used.

We claim:-

1. A curling iron, comprising a handle, a tube carried thereby, means arranged on the interior of the tube for heating the same, a 65 plate pivotally mounted on the forward end of the handle, and a swinging leg pivotally connected to the forward end of said plate.

2. A curling iron, constructed with a handle, a tube carried thereby, an electric heater 70 arranged in said tube, means arranged in the handle whereby the electric heater is controlled, a plate pivotally arranged on the forward end of the handle and adapted to swing at right angles thereto, a swinging leg pivotally arranged on the forward end of the plate, and a spring arranged between said plate and the rear end of said leg.

In testimony whereof, we have signed our names to this specification, in presence of two 80 subscribing witnesses.
